UNITED STATES PATENT OFFICE.

CARL SCHÜTZ, OF ESSEN, GERMANY, ASSIGNOR TO FRIED. KRUPP AKTIENGESELLSCHAFT, OF ESSEN-ON-THE-RUHR, GERMANY.

SELF-DISCHARGING CAR.

1,403,713.

Specification of Letters Patent. Patented Jan. 17, 1922.

Application filed February 14, 1921. Serial No. 444,863.

To all whom it may concern:

Be it known that I, CARL SCHÜTZ, residing at Essen, Germany, a citizen of the German Republic, have invented a certain 5 new and useful Improvement in Self-Discharging Cars, (for which I have filed an application in Germany, July 16, 1919,) of which the following is a specification.

This invention relates to selfdischarging 10 cars having stationary end walls and a flat, tiltable bottom, and in which the side wall located on the discharge side is suspended by a link, whereas the opposite side wall, which is articulated to the bottom is adapt- 15 ed to shift toward the discharge side when the bottom comes to be tilted. The object of the invention is to provide for cars of this kind an arrangement which will enable the discharging operation to be satisfac- 20 torily carried out even in the event of the goods lodged in the middle of the car when loaded considerably protruding beyond the upper edge of the loading room.

The invention will be further described 25 with reference to the accompanying drawing which illustrates by way of example, one embodiment of the subject matter of the present invention and in which:

Fig. 1 is an end view of the car ready for 30 loading and

Fig. 2 is a like view of the car when in the discharging position.

Referring to the drawing, the two end wells A¹ are rigidly fixed to the underframe 35 A of the car. The bottom B is mounted to rotate by aid of an axis b¹ on the underframe A; the said axis being located on the side of the car remote from the discharging side. The side wall C, disposed on the same 40 side as the axis b¹, is articulated to the bottom B and is guided in its motion in the known manner by means of rods D, engaging the upper edge of said side wall, in such wise that during the discharging action the side 45 wall C will remain substantially parallel to itself (Fig. 2.) The other side wall, E, is suspended at its upper edge on each side by means of a pin F in one arm G of a two- 50 armed lever which is fixed to the adjacent end wall A¹. The opposite arm G¹ of this lever is united by means of a connecting rod H to an extension, disposed toward the dis- 55 charge side, of the rod D located on the same end wall of the car. The side wall E is pro- vided at its lower edge with a plurality of

claws e¹ by aid of which it is enabled to engage the underside of the bottom B and to fix it in the position ready for loading. A connecting rod J, belonging to a crank mechanism operated by means of a hand-crank K, engages the side wall E; the said crank mechanism serving to either fix the side wall E in the position ready for loading, or else to shift the said wall E outward for the purpose of enabling the discharge to be carried out, and in which case the claws e¹, arranged on this wall disengage from the bottom B, so that this latter may now tilt sideways.

The manner of operation of the described 70 car is as follows:

When the car is to be discharged, the crank K is turned in suchwise that the side wall E will swing outward about the axis of the pins F, the claws e¹ at the same time 75 releasing the bottom B. Then, the weight of the goods causes the bottom B to tilt in the direction indicated by the arrow x (Fig. 1) owing to the fact that the axis b¹ is mounted laterally, the side wall C, articulated to the bottom B, hereby being raised and displaced substantially parallel to itself 80 toward the discharge side. Simultaneously, the pins F arranged on either end of the car and by which the side wall E is suspended, 85 are shifted outward by the lever mechanism D H G¹ G, in positive dependency upon the tilting motion effected by the bottom B.

The car having been discharged, the mov- 90 able parts B, C, D, H, G¹, G and F thereof are swung back into their initial positions, whereupon, by returning the crank K and therewith the connecting rod J, the side wall E is drawn with its lower edge toward the 95 car again, so that the claws e¹ re-engage the bottom B and thus close the car.

By the hereinbefore described arrange- 100 ment there is secured the advantage that the reduction of the loading room produced with the customary type of selfdischarging cars hereinbefore referred to on the dis- 105 charge operation, will, owing to the parallel displacement of the side wall facing the discharge side, be either entirely or partly com- pensated for by the upper edge of the other side wall (E) being shifted outward. For this reason, even in the event of the goods, previous to the discharge, protruding in the middle considerably beyond the upper edge 110

of the loading room, there will be created no liability of the goods, while discharging, clogging up the space between the bottom and the upper edge of the side wall E.

5 I claim:

1. A self-discharging car of the class described comprising a pivoted bottom, stationary end walls, a side wall hingedly connected to said bottom and adapted to move to-
ward the discharge side of the car during a tilting motion of the bottom, a wall disposed on the discharge side of the car, means for supporting this last named wall whereby it may be moved outwardly during a tilting motion of the bottom and in positive dependency upon this motion.

2. A self-discharging car of the class described comprising a tiltable bottom, a pair of stationary end walls, a side wall articulated to said bottom and adapted to move towards the discharge side of said car during a tilting motion of the bottom, a second side wall for the discharge side of said car, levers supporting said side wall and means 25 rotating said levers in a direction to move outward said side wall away from said car during a tilting motion of said bottom.

3. A self-discharging car of the class described comprising a tiltable bottom, a pair of stationary end walls, a side wall articulated to said bottom and adapted to move towards the discharge side of said car during a tilting motion of the bottom, a second side wall for the discharge side of said car, 30 double armed levers supporting said side wall and means connecting said double

armed levers to the first mentioned side wall whereby said second side wall will be moved outward away from said car during a tilting motion of said bottom.

40

4. A self-discharging car of the class described comprising an underframe, a flat tiltable bottom pivotally mounted on said under frame on the side thereof removed from the discharge side of said car, a side 45 wall articulated to said bottom and adapted to be displaced substantially parallel to itself toward the discharge side of said car during a tilting motion of the bottom, a second side wall for the discharge side of said 50 car, a pair of double armed levers mounted upon said end walls, one arm of each of said double armed levers being pivotally connected to said second side wall, connecting rods operatively connecting the other arms 55 of said double armed levers to said first mentioned side wall, means carried by said second side wall for engagement with said tiltable bottom, a hand crank and means connecting said hand crank to said second 60 side wall for causing it to disengage said tiltable bottom whereby said bottom may tilt and the connection between said first and second side walls cause said second side wall to swing free of said car.

65

The foregoing specification signed at Essen, Germany, this 15th day of November, 1920.

CARL SCHÜTZ.
